UNITED STATES PATENT OFFICE.

JOHANN GEORG FAHR, OF GOTTMADINGEN, GERMANY, ASSIGNOR TO MASCHINEN-FABRIK FAHR/A.-G., OF GOTTMADINGEN, GERMANY.

MOWING-MACHINE.

1,115,797.

Specification of Letters Patent.

Patented Nov. 3, 1914.

Application filed July 8, 1910. Serial No. 570,988.

To all whom it may concern:

Be it known that I, JOHANN GEORG FAHR, a citizen of the German Empire, residing at Gottmadingen, in the Grand Duchy of 5 Baden, Germany, have invented certain new and useful Improvements in Mowing-Machines, of which the following is a specification.

My invention relates to harvesters, reapers, mowers and the like having lifting and swinging cutters, in which the upward movement of the cutter-bar is derived from the forward movement of the machine.

The essential feature of my improved 15 mowing-machine consists in the disconnection and connection of the cutter actuating mechanism being effected by the forward movement of the machine in addition to the lifting of the cutters being so effected.

20 Further, in my machine are embodied improvements which serve to simplify and control the descent of the cutter-bar. Such improvements are imperative, because in the present machine a handle for moving the 25 cutter-bar is not provided, but the descent is effected automatically by gravity after the release thereof.

The simplification of the descent of the cutter-bar is provided by a contrivance, 30 which during the descent of the bar places out of action a bolt, which on raising the bar holds this latter in an intermediate position, so that the bar can be let down from the highest position to the ground without a repeated disengagement of the retaining means.

40 The control of the descent of the bar is provided by avoidance of a defect which is, that on descent of the cutters, from the vertical position, frequently the dragbar first descends almost to the earth and only thereafter the actual outwardly extending cutter-bar assumes the horizontal position, whereby prejudicial strains are set up in the machine, which often lead to breakages. This 45 defect is avoided, by the provision of a supporting hook on the frame of the machine, which first limits the descent of the dragbar, and after the cutter-bar has assumed the horizontal position, subsequently automatically releases the former. The hook is actuated by a portion of the lifting mechanism, by preference, the curved link to which the lifting spring is secured.

An example of a mowing and reaping 55 machine constructed according to my inven-

tion is illustrated on the accompanying drawings, certain parts not necessary for explaining the invention, being omitted in said drawings.

Figures 1 to 3 are side elevations partly 60 in section of the machine, of which Fig. 1 shows the operative position of the parts with the cutter mechanism let down, Fig. 2 with the cutter mechanism raised to swath height (intermediate height) and Fig. 3 65 with the same raised into its terminal vertical position. Figs. 4 and 4^a are detail plan views. Fig. 5 is a rear elevation of the machine. Figs. 6 to 9 show a detail of the contrivance for simplifying the descent of 70 the bar, in three different positions. Fig. 10 is a fragmentary rear elevation view of the wheel and axle, showing the gears in operative engagement, the inoperative being indicated in dotted lines. Fig. 11 is a sectional 75 elevation view of the gears showing them in the operative position, this view being taken to the left of the wheel shown in Fig. 10.

The lifting lever 1, by means of which and 80 the lever 1^a and link 1^b the cutter-bar is raised and swung into the vertical position in the known manner, is connected by a chain 4 with the chain roller 30, mounted on a shaft 6. This shaft is so mounted in the 85 frame of the machine by one of its bearings 7 as to be adapted to be rocked from a downwardly inclined position of rest, upward into a position parallel to the axle of the track wheels, depicted in Fig. 4. In this position 90 the pinion 9 of the shaft 6 gears with the spur-wheel 10 of the track-wheel axle. Consequently, on the machine traveling, if the shaft 6 is brought into the parallel position, the shaft 6 is rotated and the chain 4 wound 95 up, causing the lifting lever to be displaced angularly and the cutter-bar to be raised. The shaft 6 is raised from the inclined position to the parallel position by a pedal 12, which through the agency of a shaft 13 and 100 an arm 15 lifts the movable bearing 17 and by means thereof the shaft 6.

Above the shaft 13 is the shaft 34, journaled in the frame, which controls the disconnection and connection of the cutter-driving 105 mechanism. To this shaft is secured the arm 47 which, by means of the link hook 60 releases and engages the clutch between the driving wheel and the blade. Mounted on the shaft 34 is a cam lever 33, which is under 110

the influence of a helical spring 32, which presses it downward against the periphery of a cam disk 31 mounted on the shaft 6. This disk is of such profile that the elevated portions thereof press the lever 33 so far upward that the cutter driving mechanism is disconnected by the medium of the arms 47 and 60, whereas on the lever bearing against the depressed portions, the shaft 34 10 assumes the position which effects the driving or operating connection of the cutter mechanism. As on swinging up of the cutter-bar the pinion 9 of the shaft 6 is brought into engagement with the spur wheel 10, the 15 cam disk 31 rotates when this engagement has been effected, so that by the driving power of the carriage, by means of the shaft 6 and cam 31, the shaft 34 is rotated and disconnection of the cutter mechanism is 20 effected.

The disk which effects the disconnection, instead of being mounted on the shaft 34, could be mounted on a separate shaft which, on disconnection being required is either 25 brought by a separate pedal into engagement with the wheel 10, or with some other portion of the machine which, actuated by the forward motion, or may be automatically brought into the engaging position by the 30 movement of the lifting gear.

If, from time to time, during the operation of the machine it is desired to raise the cutter-bar into an intermediate position (to the so-called swath height) without employing 35 the automatic power drive, this can be effected by a pedal 46, which is pivotally mounted on a pin of the lifting lever and acts, on depression, against an abutment 48.

When it is desired to raise the cutter to 40 the intermediate position the cam-lever 33 which effects the disconnection and connection is arranged at the rear end, alongside a cam surface provided on the lifting disk 28. This disk 28 is rotated on movement of 45 the lifting lever 1 by means of a link 29, so that the appropriately shaped cam-surface supports the cam-lever 33, for the time being, in the requisite position. This is necessary in cases when the cutters under exceptional circumstances are lifted from the 50 ground without employing power. The shaft 6 does not then participate in the rotation, and consequently the cutter mechanism would remain connected, were the disconnection in such case not effected by the said cam-surface.

The descent of the cutters from the vertical position results by the action of gravity, after a pedal 41, provided for this purpose, 55 has released the detent, which retains the bar in the vertical position, and has initiated the descent. In order that the detent on reaching, during the descent, the usual intermediate position shall not become operative, a 60 contrivance is provided, which consists

broadly of a masking lever mounted loosely on the spindle or nave of the lifting lever, which under the influence of its weight assumes such a position on descent of the bar as to prevent the entry of the bolt of the 70 detent into the notch which corresponds to the swath-high position (intermediate position) of the bar, while on the other hand it is of such configuration, that on lifting the bar it is forced by the detent bolt itself out 75 of the position which prevents the entry into the intermediate notch.

The detailed construction of the contrivance is as follows: On the main frame 8 is provided in the known manner the segmental rack comprising three notches 49, 80 50, 51 for the engagement of the detent bolt 39, within a bearing 39a, which is under the influence of a spring. Notch 49 corresponds to the lowermost position of the cutters, 85 notch 50 to the intermediate position (swath-height) and notch 51 to the vertical position of the cutter-bar. The detent bolt 39 can be displaced against the thrust of the spring by the pedal 41, whereby it is moved 90 out of the path of the rack. On the nave of the lifting lever 1 is loosely mounted the masking lever 38, which by virtue of the weight 43 of its rear end, tends to bear with its nose 45 against a fixed abutment 42. In 95 this position the front end 45 is so situated as to mask the intermediate notch 50 and prevent entry of the detent bolt 39.

On the lifting lever being moved in the direction of the arrow 52 from the lowermost position, corresponding to the notch 49, the detent bolt encounters the nose of the front end of the masking lever 38 and causes same to participate in its further travel, so that thereby engagement of the bolt 39 in 100 the intermediate notch 50 and in the notch 51 farther on is not prevented. The length of the front end 45 of the masking lever is such relatively to the radii of the rack, that this front end 45 is released as the detent 105 bolt passes from the notch 50 to the notch 51. The masking lever thereupon falls back into its position of rest, shown in Figs. 6 and 8, and, when by actuating the pedal 41 the detent bolt is subsequently disengaged 110 from its position in the notch 51, which maintains the cutter bar vertical, and the latter descends, the bolt cannot on its return engage in the intermediate notch 50, because it is forced up by the masking lever 115 and prevented from entering the groove. Thus it is insured that the intermediate notch is operative only during the lifting of the cutters and not during the descent thereof.

With the above described contrivance for automatically disconnecting and connecting the cutter mechanism and the direct descent of the cutter bar from the vertical position to the bottom position, it may happen that 120 125 130

the drag-bar 37, to which the cutter-bar is pivotally connected, and the cutter-bar may at times assume a mutual angular position in which the drive of the cutters is obstructed, while the driving mechanism has been connected by the automatic clutch. This defect, which might lead to breakage of parts of the cutter gear, is avoided by so controlling the descent of the bars, that the 10 drag-bar is prevented, by a supporting hook actuated by the lifting gear, from completing its descent, while the cutter bar has not yet reached the horizontal position. This supporting hook 35 is pivotally mounted on 15 the frame 8 of the machine. A prolongation 53 of the hook 35 is situated in the path of the end 54 of the curved link 36, to which the lifting spring 55 is secured in the known manner. Normally this hook 35 hangs vertically downward by virtue of its weight and supports the arm 37 of the drag-bar, as shown in Fig. 2. During the descent of the bars the end 54 of the curved link 36 moves toward the left and, when the cutter bar has 20 assumed its horizontal position, encounters the extension 53, so that the hook 35 assumes an inclined position, as shown in Fig. 1, thereby releasing the arm 37 of the drag-bar, so that the same falls.

30 On lifting the bar the extension 53 of the

hook is left by the end 54 of the link only when the drag-bar has reached its highest position (swath-height). The hook then falls against the arm and supports it during the further course of the lifting movement 25 of the cutter-bar and during the succeeding descent until, at the end of the latter as above described, it is again thrown off and again releases the drag-bar.

I claim:

In a mowing and reaping machine of the character described having cutters and driving mechanism therefor, means for lifting said cutters by power derived from the forward movement of the machine, a detent 45 connected with said lifting means, a quadrant having a series of notches on its edge, attached to the machine and in position to be engaged by said detent, and means for holding the detent from engagement with an 50 intermediate notch when the cutter is being lowered, said means being inoperative to prevent said engagement when the cutter is raised.

In testimony whereof I affix my signature 55 in presence of two witnesses.

JOHANN GEORG FAHR.
